ATTORNEY.

UNITED STATES PATENT OFFICE.

MICHAEL HALLANAN, OF NEW YORK, N. Y.

DESIGN FOR A HORSESHOE-PAD.

SPECIFICATION forming part of Design No. 20,849, dated June 23, 1891.

Application filed May 6, 1891. Serial No. 391,824. Term of patent 14 years.

To all whom it may concern:

Be it known that I, MICHAEL HALLANAN, a citizen of the United States, residing at the city, county, and State of New York, have invented and produced a new and original Design for Horseshoe-Pads, of which the following is a description.

Reference is to be had to the accompanying drawings, forming a part of this specification, in which—

Figure 1 is a face view of a horseshoe-pad embodying my new design, and Fig. 2 a cross-section through line $x-x$ of Fig. 1.

The invention relates to pads having a leather backing, the latter to be secured to the hoof with the shoe; and my design consists in the peculiar configuration of the pads shown. The marginal contour of the backing C may be varied, as it does not form part of the design. The pad A is in general of horseshoe shape, and the inner wall a thereof is beveled inward and downward. The outer marginal line a' of the face of the pad A

merges into the outer transversely-ranging line b of the horizontal face of the pad B, and the inner marginal line a² of the face of pad A merges into the inner transversely-ranging marginal line of the horizontal face b' of pad B. The lines of the pad B depart forwardly and downwardly within the pad A from the line b', the forward defining-line b² of the pad B being curved, and the said pad between the lines b' b² being transversely convexed. The faces of the pads A B and the inner wall of the pad A are ornamented with rectangular depressions c, the bottoms of which converge to a common center; but such surface ornamentation may be varied.

I claim—

The design for horseshoe-pads herein shown and described.

MICHAEL HALLANAN.
